UNITED STATES PATENT OFFICE.

HUBERT K. WOOD, OF BAYSIDE, NEW YORK, ASSIGNOR TO ELECTRIC FLASHER COMPANY, OF NEW YORK, N. Y., A CORPORATION OF NEW YORK.

CONTROLLER-OPERATING MECHANISM.

1,366,996.

Specification of Letters Patent.

Patented Feb. 1, 1921.

Application filed April 19, 1917. Serial No. 163,163.

To all whom it may concern:

Be it known that I, HUBERT K. Wood, a citizen of the United States of America, residing in Bayside, Queens county, Long Island, State of New York, have invented certain new and useful Improvements in Controller-Operating Mechanism, of which the following is a specification.

This invention relates to controller operating mechanism and aims to provide improvements therein. The invention relates more especially to an electric switch operating mechanism, the switch effecting two or more controls.

15 There are at the present time controller or switch operating mechanisms which effect the distribution, or making and breaking of one or more electric circuits at desired times. For example, in apartment houses it may be 20 desirable to turn on the hall lights at a certain hour of the evening and to turn them off at an hour in the morning, or allow these lights to burn for a period, then cut out half the number of lights, and in the morning to cut out all of the lights.

It frequently happens, however, that it is desirable to put on lights before the time when it is usual to put them on. In previous apparatus permitting of effecting controls at times other than that at which the mechanism is set to act, such irregular or untimely operation may result in disordering the subsequent series of controls. For instance, where lights have been put on prior 35 to the time for ordinarily being put on, the means for effecting the cutting out of half the lights may operate to cut out half the lights at the time when normally all of the lights are put on, and at the time when half 40 the lights are to be cut out, the means for cutting out all of the lights may act.

The present invention provides means whereby the foregoing objections are avoided, and whereby controls may be effected at times other than the usual time, and whereby the subsequent sequence of controls may be effected by the apparatus as effectively and as regularly as though the untimely control had not been effected.

50 An embodiment of the invention is illustrated in the accompanying drawings, wherein—

Figure 1 is a top plan view thereof;

Fig. 2 is a sectional view, following generally the line II—II Fig. 3, and

Fig. 3 is a side view.

In said drawings the letter A designates a suitable controller, here shown as an "on and off" electric switch; B designates a motor or actuating mechanism for actuating the controller A, and C designates a mechanism for controlling the operation of the actuating mechanism B. The mechanism C is here shown as a clock-actuated mechanism, in direct proximity to the motor mechanism B, but other means for actuating the motor mechanism B may be employed. Furthermore, clock mechanism remote from the motor mechanism B may be employed.

The clock-actuating mechanism C may be of usual construction, comprising a main spring and escapement, and also comprises a dial c actuated by the clock mechanism to turn at a desired speed. As here shown, the dial is adapted to make one revolution in twenty-four (24) hours, and the dial preferably bears thereon numerals indicating the hours of the day and night. The dial c, or an associated part, carries a plurality of actuators c', c², one actuator being provided 50 for each control to be effected by the switch controller A. The actuators c', c² are preferably adjustable with relation to the dial, and are provided with handles c³, by which they may be conveniently moved. In order to designate the individual handles, they may be made of different form, as here indicated, one being shown as round and the other being shown as square.

The actuating mechanism B preferably 90 comprises a spring motor b driving a train of gears b', b'', b³, b⁴, the gear b'' actuating a gear a upon the switch or controller. A suitable governor, as a fan governor b², may be provided for controlling the running of the motor b. A suitable detent mechanism b³ is provided for controlling the running of the motor b. The detent mechanism comprises a detent b⁴, b⁵, etc., for each control to be effected by the switch or controller A. 100 The detents may act to control the running of the motor in any suitable way, the detents being here shown as acting upon the fan governor b². The detents b⁴, b⁵, etc., have parts, as pins b⁷, b⁸, which are struck 105 by the actuators c', c², each actuator being mounted in a plane so as to strike or actuate but one detent.

Means are provided for holding all of the detents out of operative relation with the 110

actuators c' , c^2 , except the detenent which effects the next control in the ordinary sequence of operations. By this arrangement all of the actuators pass idly by the detents, 5 except the actuator corresponding with the next control in the ordinary sequence. These means preferably comprise a plurality of notched disks b^{10} , b^{11} , etc., actuated by suitable means, as gearing b^0 , b^1 , to turn 10 at a speed related to the movements of the controller A. The detents are provided with suitable means, as pins b^{12} , b^{13} , for engaging the notched disks. The detents are normally pressed by springs b^{14} in a direction to engage the fan governor b^2 .

Operation: The operation of the embodiment herein shown and specifically described will be given as illustrative of the operation of the invention.

20 In Fig. 1 the switch is shown as being in "off" position. The pin b^{13} of the detent b^5 rests against the periphery of its corresponding disk b^{11} . The detent b^4 having its pin b^{12} in the notch in the disk b^{10} , is pushed 25 forward by its spring b^{14} and engages the fan governor b^2 and holds the motor mechanism B and the switch or controller mechanism A against movement.

The dial c of the clock-actuating mechanism C, traveling in the direction of the arrow, in course of time brings the actuator c' into contact with the pin b^7 upon the detent b^4 . The contact of the actuator c' upon the detent b^4 moves the detent b^4 out of engagement with the fan controller b^2 , thereby permitting the motor to act, the motor through the gearing b' , b'' , and a turning the switch or controller A. The actuator c' at the same time that it effects the disengagement of the detent b^4 and the fan controller, lifts the pin b^{12} of the detent b^4 out of the notch in the disk b^{10} . The lifting of the pin on the detent out of the notch in the disk may be assisted by a cam-action of the 45 notch under the force of the motor B. The motor mechanism B continues to turn the switch or controller A until the disk b^{11} comes into position to allow the pin upon the detent b^5 to fall into the notch in the 50 said disk b^{11} , whereupon one of the springs b^{14} pushes the said detent b^5 forward into position to engage and stop the movement of the fan governor b^2 , whereupon the movement of the motor mechanism B and the 55 controller mechanism A is stopped. The relation between the degrees of rotation of the shaft bearing the disks b^{10} , b^{11} , etc., and the switch, is such that the switch or controller effects the desired change of control 60 during the time the series of notched disks b^{10} , b^{11} , etc., is released by one detent and stopped by another. For example, supposing the controller A to be one that effects a control in a quarter-turn, i. e., effects an 65 "on" and an "off" control in a half revolu-

tion, the gears b^0 and b'' being equal and remaining the same, the gear b^0 would have half the number of teeth of the gear a . Should the control be one which effected four different controls in one revolution, the 70 gear b^0 would be made of the same number of teeth as the gear a , and four notched disks provided, instead of two, with the notches 90° apart.

After the aforementioned operation of the 75 mechanism, the switch or controller in Fig. 1 will be in the "on" position. The actuator c^2 will, in its appropriate time, moving in the direction of the arrow, come into contact with the pin b^8 (Fig. 3) upon the detent 80 b^5 , lifting the detent b^5 , thereby releasing the fan controller b^2 and permitting the motor mechanism B to actuate the controller or switch mechanism A to effect the next control, viz: to turn the switch to "off" 85 position.

Referring again to Fig. 1 (with the switch in "off" position), supposing it being desired to turn the controller to "on" position prior to the time that the actuator c' would ordinarily move around to the position to actuate the detent b^4 , the detent b^4 may be moved by hand, or other means, to release the fan governor mechanism b^2 , whereupon the motor will be released and turn the 95 switch or controller to "on" position. The motor mechanism B will be stopped by the detent b^5 (the pin upon the detent b^5 dropping into the notch upon the disk b^{11} and allowing the detent b^5 to be pressed forward and engage the fan controller b^2), and when the motor is stopped in the "on" position, the pin b^{12} upon the detent b^4 will rest upon the periphery of the disk b^{10} , and consequently hold the pin b^7 thereon out of position to be 100 struck by the actuator c' . Consequently, when the actuator c' is turned in course of time to the position where it would contact with the detent b^4 , the detent b^4 will be out of position to contact with the actuator c' , and consequently the actuator c' , will pass idly by the detent b^4 . The dial c continuing to turn will bring the actuator c^2 around to contact with the detent b^5 (effecting the "off" position of the switch) in the regular 110 lapse of time, and the mechanism will act, and continue to act regularly, as if the controller had not been actuated out of its ordinary time by the manual operation of the detent.

To operate a switch or control having a greater number of controls than two, the mechanism B would be provided with a number of disks and detents corresponding to the number of controls, and the clock-actuating mechanism C would also be provided with a number of actuators corresponding to the number of controls.

By omitting the clock-actuating mechanism C, the detents of the motor mechanism 120 125 130

B may be manually operated to effect controls of the controller or switch A.

The inventive idea herein set forth may be expressed in other mechanical embodiments than that herein specifically described and illustrated.

What I claim is:—

1. Controller operating mechanism, comprising a controller, a motor for operating said controller, detent mechanism and means for operating said detent mechanism, said detent mechanism comprising a plurality of detents, each of said detents being independent of the other, and a plurality of notched disks, said notched disks being adapted to hold all but one detent at a time out of position to be actuated by said means for operating the detent mechanism, said motor comprising a governor adapted to be engaged by the detents.

2. Controller operating mechanism, comprising a controller, a motor for operating said controller, detent mechanism and clock-actuated means for operating said detent mechanism, said detent mechanism comprising a plurality of detents, each of said detents being independent of the other, and a plurality of notched disks, said notched disks being adapted to hold all but one detent at a time out of position to be actuated by said clock-actuated means for operating the detent mechanism, said motor comprising a governor adapted to be engaged by the detents.

3. Controller operating mechanism, comprising a controller, a motor for operating said controller, detent mechanism and means for operating said detent mechanism, said detent mechanism comprising a plurality of detents, each of said detents being independent of the other, and a plurality of notched disks, said notched disks being adapted to hold all but one detent at a time out of position to be actuated by said means for operating the detent mechanism, said motor comprising a part connected with the rotor of said motor adapted to be engaged by the detents.

4. Controller operating mechanism, comprising a controller, a motor for operating said controller, detent mechanism and clock-actuated means for operating said detent mechanism, said motor comprising a governor adapted to be engaged by the detents, and said detent mechanism comprising a plurality of detents, each of said detents being independent of the other, and means adapted to hold all but one detent at a time out of position to be actuated by said means for operating the detent mechanism, whereby if one detent be actuated by other than its normal operating means, such detent will be moved out of operating position with respect to its normal operating means, and the next detent in the sequence moved into operative position to be actuated by the operating means at the time when said operating means would normally actuate said last-named detent.

5. Controller operating mechanism, comprising a controller, a motor for operating said controller, a governor for controlling said motor, detent mechanism, and clock actuated means for operating said detent mechanism, said detent mechanism comprising a plurality of detents, each of said detents being independent of the other, and means adapted to hold all but one detent at a time out of position to be actuated by said means for operating the detent mechanism, whereby if one detent be actuated by other than its normal operating means, such detent will be moved out of operating position with respect to its normal operating means, and the next detent in the sequence moved into operative position to be actuated by the operating means at the time when said operating means would normally actuate said last-named detent.

In witness whereof I have hereunto signed my name in the presence of two subscribing witnesses.
